UNITED STATES PATENT OFFICE.

JACOB N. LARSEN, OF PRESTON, IDAHO, ASSIGNOR TO WESTERN BOOK AND MANUFACTURING COMPANY, OF LOGAN, UTAH, A CORPORATION OF UTAH.

LOOSE-LEAF BINDER.

971,202.

Specification of Letters Patent. Patented Sept. 27, 1910.

Application filed February 10, 1910. Serial No. 543,006.

To all whom it may concern:

Be it known that I, JACOB N. LARSEN, a citizen of the United States, and a resident of Preston, Oneida county, State of Idaho, have invented a certain new and useful 5 Loose-Leaf Binder, of which the following is a specification.

This invention is a loose leaf binder embodying an improvement upon, or an addition to, the loose leaf binder forming the 10 subject matter of a prior patent, No. 921,467, granted May 11, 1909, upon an application of J. Schaub and J. N. Larsen.

The salient feature of the present invention 15 consists of a binder so constructed that none of the leaves can be removed therefrom without employing a special key which permits the operation of a member, preferably a locking slide, whereby one of the covers 20 of the binder is released, whereupon one or a plurality of leaves may be removed, and, if desired, replaced by others, the key in the meantime becoming secured to said cover and remaining so secured until the said locking slide is manually operated to return it 25 to its normal position.

More specifically stated, the invention embodies a binder plate provided with a keeper for the locking key and with a grooved member into which a grooved locking key is 30 adapted to slide, a lock-easing fixed to said binder plate and having grooved flanges adapted to receive the grooved locking key, a post-locking slide having pintles to engage with the posts and provided, also, with shoulders and notches, and locking bolts 35 slidably fitted between the flanges and within the lock easing so that they may be actuated by the insertion and withdrawal of the key. The bolts are so positioned and operated that, when the key is withdrawn, they will engage the shouldered notched slide to preclude movement thereof, but when the key is inserted into the keeper and into the 40 grooved member and the grooved flanges of the binder plate and the lock easing, respectively, certain of said bolts are withdrawn from the slide and other bolts are thrown into engagement with the key for the purpose of retaining said key in a locked position during the time that the slide is released from the posts. This is important 45 for the reason that it indicates to the book keeper that the binder is unlocked, and when

the key is attempted to be withdrawn, the book keeper must first adjust and lock the slide so as to lock the posts and the leaves of the book before removal of the key.

Other features of the invention will be apparent from the following detailed description.

In the accompanying drawings there is illustrated one practical embodiment of the invention, but the construction shown therein is to be understood as illustrative, only, and not as defining the limits of the invention.

Figure 1 is a perspective view illustrating a binder partly filled with leaves and constructed in accordance with the invention. Fig. 2 is a section on the line 2-2 of Fig. 1. Fig. 3 is a plan view, on an enlarged scale, illustrating a part of the binder plate, the locking mechanism and certain parts associated therewith, said locking mechanism being represented in position for locking the post-locking slide against movement. Fig. 4 is a view similar to Fig. 3 showing the key in the locking mechanism for the purpose of releasing the locking bolts from the post-locking slide, and for retaining said key within a keeper of the binder plate. Fig. 5 is a plan view of the post-locking slide removed from the binder. Figs. 6 and 7 are cross sections on the lines 6-6 and 7-7 respectively, of Fig. 3.

In Figs. 1 and 2 the binder is shown as having covers, A, A', and posts, B, on which are fitted the leaves, C. Cover, A', is provided with a plate, a, on the inner side of said cover, and to this plate is connected one end of a series of posts, B, preferably by means of pintles, b. The other cover, A, is shown as being provided with a binder plate, D, which is secured firmly to the inner face 95 of said cover, A, said cover having a recess, d, shown more particularly in Fig. 2.

Binder plate, D, is shown in Figs. 3, 4, 6 and 7, and at one edge said binder plate is provided with eyes, d', which are separated 100 by intervening slots, d''. The binder plate is provided, furthermore, with a longitudinal slot, e, and near one edge of said binder plate it is depressed, as at e', so as to form a longitudinal channel, said channel being 105 adapted for the reception of the locking key, E, whereby the depression and channel operate as a keeper for said locking key.

F designates a locking slide which is provided on one of its edges with a series of angle slots, f , and with pintles, f' , see Fig. 5. Near one end the locking slide is provided with raised transverse flanges, g , which are preferably knurled, said flanges being positioned for operation in the longitudinal slot, e , of the binder plate, whereby the flanges serve the purpose of thumb pieces against which pressure may be applied by hand for the purpose of adjusting the slide lengthwise of the binder plate. An edge portion of slide, F, is fitted within the alined eyes, d' , of the binder plate, and this edge of the slide, together with pintles, f' , are adapted to move in said eyes, d' , whereby the slide is connected to the binder plate, and said slide may be moved in the direction of its length by applying pressure to thumb pieces, g . Slide, F, is positioned intermediate the binder plate and cover, A, as shown more particularly in Fig. 2, and thus the slide is concealed from view, except that part thereof which is opposite to slot, e , of said binder plate.

Locking slide, F, is provided with a flange, h , extending lengthwise thereof at one end portion of the slide, and on the opposite edge from pintles, f' . This flange is produced on the slide by increasing the width of one end portion thereof so that the flange lies in the plane of the slide, and in this flange are notches, h' , which are separated so as to produce shoulders, h^2 .

The binder plate, D, is provided at one end of the keeper, e' , with a serrated or corrugated member, d^3 , see Fig. 1, and into this grooved member is adapted to slide a grooved part, E' , of the locking key, E, the latter being shown in Fig. 4.

G designates a lock-casing which is fixed to binder plate, D, in a position close to slot, e , and keeper, e' , see Figs. 3, 4, 6 and 7. This lock-casing is compact in construction and attached rigidly in a suitable way to the binder plate, whereby the locking mechanism is brought into coöperative relation to keeper, e' , and to the notched and shouldered part of post locking slide, F. The lock-casing is provided interiorly thereof with flanges, g' , which are parallel to each other so as to provide intermediate spaces for the reception of bolts, H, H', and I, I', said flanges serving the purpose of guides for the sliding bolts. The flanges extend across the path of the key when the latter is moved within keeper, e' , so as to be inserted into the lock-casing, and in said end portions of the flanges are provided grooves, g^2 , adapted to receive the grooved part, E' , of the key. The grooved parts, g^2 , of the flanges and the grooved member, d^3 , of the binder plate preclude the insertion of any key except one having grooves corresponding to said parts, g^2 , d^3 .

Bolts, H, H', are provided with teeth, h^3 , and with these teeth mesh the teeth of a gear wheel, J, the latter being fitted loosely on a stud or journal, j , projecting from one of the flanges, g' . The bolts, I, I', of the other pair are provided with gear teeth, i , which mesh with the teeth of a gear, J' , loosely mounted on a stud or journal, j' , of another of the flanges, g' , see Figs. 3 and 4. The gear, J, thus operatively connects bolts, H, 70 H', for simultaneous movement in opposite directions, and similarly the other gear, J' , connects bolts, I, I', to insure simultaneous movement in opposite directions to said bolts, I, I'. Each bolt is provided at one 80 end with a bevel, k , adapted to enter a notch, h' , of the post locking slide, F, whereby the slide is adapted to be securely locked in position when its pintles, f' , engage with the eyes in the upper ends of posts, B, thus precluding any one from manipulating slide, F, and opening the binder, except when key, E, is inserted into the locking mechanism.

Bolts, H', I, are shown as being provided with recesses, l , in which are fitted coiled springs, L, one end of each spring acting against one of the bolts, while the other end of the spring is seated against a stop plate, l' , said stop plate being fixed to one of the flanges, g' , and extending into recesses, l , 90 of said bolts, H', I. It will thus be seen that one spring acts to impel bolt, H', in one direction, and this bolt acts on gear, J, to move the companion bolt, H, of the pair into engagement with a shoulder of locking 100 slide, F. In a similar manner the other spring, L, acts on bolt, I, which turns gear, J' , for the purpose of moving the companion bolt, I', of the pair, I, I', so that the bolt, I', will enter a notch of slide, F, the bolts, H, 105 I', acting to lock the slide in an operative position.

The bolts, H', I, are provided with rounded ends, m , said rounded ends of the bolts being opposite to the grooved parts, g^2 , 110 of flanges, g' , whereby the rounded ends, m , are in the path of the key, E.

As in the prior patent referred to, the binder embodies in its construction a series of posts, B, each of which is provided at one 115 or both ends with openings adapted to receive the pintles on the locking slide. The end of each post is received in one of the series of slots, f , and when the slide is moved to an operative position, pintles, f' , enter 120 the openings in said posts, B, whereby the posts are connected to, and locked by, the pintles of slide, F, so that the leaves cannot be removed or tampered with. Prior to adjusting slide, F, to its locked position key, 125 E, must be withdrawn, and springs, L, impel bolts, H', I, into notches, h' , of slide, F, thereby locking the slide against endwise movement in either direction.

In order to remove any one or more of 130

leaves, C, it is necessary for the operator to place a proper key in the channel, e', of the key keeper, after which the key is inserted into the locking mechanism by moving said key longitudinally in one direction. Assuming that the key is of proper construction, it will pass the corrugated part, d², of the binder plate and the grooved parts, g², of flanges, g', whereupon the operative edge 10 of the key will engage with the rounded ends, m, of bolts, H', I, the effect of which is to press the bolts inwardly against the tension of their springs and turn gears, J, J', which will act on the other bolts, H, I', to withdraw them from engagement with the shouldered edge of slide, F, see Fig. 4. So long as the key remains in its inserted position, the operator can manipulate slide, F, by pressing on the thumb pieces, g, whereby the slide may be moved in the direction of its length and withdraw pintles, f', from the openings of posts, B, thus permitting the binder to be opened and enabling access to be obtained to any one or 20 more of leaves, C. When the slide is withdrawn to its inoperative position, key, E, remains in the keeper and the lock-casing, for the reason that rounded ends, m, of bolts, H', I, are pressed by springs, L, into engagement with the key; thus, precluding said key from being withdrawn during the time that slide, F, is in said inoperative position. In order to close and lock the binder, it must be adjusted so that the pintles of 30 locking slide, F, will enter the openings in posts, B, and the slide may be adjusted to its operative position so as to connect the pintles with said posts, B. The key may now be withdrawn from the locking mechanism by pulling it into the channel of keeper, e', whereupon the springs, L, will act on the bolts and the gears so as to impel bolts, H, I', into locking engagement with shoulders, h², of the slide, whereby the slide is locked in an operative position and the leaves, C, cannot be removed from the binder.

While the binder is shown as having on one cover a single binder plate, a locking slide, and a key-actuated lock, it may be, and preferably is, provided on its other cover with similar devices, whereby the two covers may be locked to posts, B, thus enabling the operator to release either end of the posts from the adjacent cover.

It is evident that the parts may be so constructed that the key may be released and withdrawn from the lock mechanism when the slide is in an inoperative position, but it is preferred to so arrange the lock mechanism that the key cannot be removed when said slide occupies a position free from engagement with posts, B.

What is claimed as new is:

1. In a loose leaf binder, a binder-plate, a

locking slide, locking mechanism coöperating with the slide, a key for releasing said locking mechanism, and means for retaining said key against removal while the locking slide is in its unlocked position.

70

2. In a loose leaf binder, a binder-plate, a locking slide, locking mechanism coöperating with the slide, and a key coöperating with the binder-plate and the locking mechanism, said key being held by the binder-plate against removal while the locking slide is in an unlocked position.

75

3. In a loose leaf binder, a binder-plate provided with a locking-key keeper, a locking slide, locking mechanism, and a key coöperating with said locking mechanism and the key keeper so that when the locking slide is in its released position the key is held in said keeper against release, but is releasable when the locking slide is in its locking position.

80

4. In a loose leaf binder, a binder-plate provided with a locking-key keeper, a post-locking slide on said binder-plate, and key-operated locking mechanism in coöperative relation to said keeper and to said slide, the arrangement being such that upon the movement of the slide to an inoperative position the locking-key will be retained in said keeper by said locking mechanism.

85

5. In a loose leaf binder, a binder-plate provided with a locking-key keeper, a post-locking slide on said binder-plate, said slide being provided with shoulders and notches, and key-operated locking mechanism carried by the binder-plate and positioned in coöperative relation to said keeper and said slide, said locking mechanism including a plurality of bolts so connected and operated that the slide is locked in its operative position and the locking key is retained in the keeper upon the movement of the slide to an inoperative position.

90

6. In a loose leaf binder, a binder-plate provided with a locking-key keeper, a post-locking slide on said binder-plate, said slide being provided with shoulders and notches, and key-operated locking mechanism carried by the binder-plate and positioned in coöperative relation to said keeper and said slide, said locking mechanism including a plurality of pairs of oppositely movable bolts and a gear connecting the bolts of each pair whereby certain of said bolts retain the slide in an operative position and other bolts retain the locking-key within the keeper upon the movement of the slide to an inoperative position.

100

7. In a loose leaf binder, a binder-plate provided with a keeper for a locking-key, a post locking slide, a lock-casing fixed on said binder-plate, grooved flanges within said lock-casing, toothed locking bolts guided by said flanges and adapted for engagement with said slide, and a gear connecting two

110

115

120

125

130

adjacent bolts and operable to move them in opposite directions, certain of said bolts being adapted for engagement with a key so that the key will be retained in the keeper when the slide is adjusted to an inoperative position.

In testimony whereof I have signed my

name to this specification in the presence of two subscribing witnesses.

JACOB N. LARSEN.
